UNITED STATES PATENT OFFICE.

WILLIAM A. PENROD, OF DAYTON, OHIO.

COOKER AND BOILER.

1,422,472.

Specification of Letters Patent.

Patented July 11, 1922.

Application filed June 10, 1920. Serial No. 387,893.

To all whom it may concern:

Be it known that I, WILLIAM A. PENROD, a citizen of the United States, residing at Dayton, in the county of Montgomery and 5 State of Ohio, have invented certain new and useful Improvements in Cookers and Boilers, of which the following is a specification.

This invention relates to domestic heaters and has special reference to that class of devices known as fireless cookers, the object of the present invention being to simplify the construction and enlarge the field of usefulness of such a device.

15 My invention contemplates the provision of means whereby a supply of hot water for domestic purposes may be quickly obtained and by the same means the cooking of food accomplished by the utilization of heat 20 given off by the hot water. To this end the invention consists in certain novel features 25 which are illustrated in the accompanying drawings and will be hereinafter first fully described and then more particularly pointed out in the appended claims.

In the drawings—

Figure 1 is a perspective view of an apparatus embodying my improvements;

Fig. 2 is a horizontal section on the line 30 2—2 of Fig. 1;

Fig. 3 is an enlarged vertical section of the cooker.

In carrying out my invention, I employ a boiler or heater consisting of a double-walled cylinder 1, the space 2 between the inner and outer walls of said cylinder being utilized as a water chamber. The top 3 and the bottom 4 of this cylinder are imperforate and the entire cylinder may be covered 35 with asbestos in order to prevent waste of heat. The cylinder is preferably provided at its lower end with feet 5 whereby it may be supported upon a shelf 6 secured to the wall of a kitchen or other room, the said 40 feet maintaining the cylinder in spaced relation to the shelf so that a burner 7 for gaseous fuel may be placed below the cylinder and permit a flame to play directly upon the bottom thereof. Water is supplied to the 45 annular chamber 2 in any preferred manner and in Fig. 1 I have shown pipes 8 and 9 which may extend to the heating furnace in the cellar of the building so that in cold weather when the furnace is 50 in use the water in the compartment 2 may be heated directly from the furnace.

These pipes 8 and 9 are provided with cut-off valves 10 so as to control the circulation of the water as will be readily understood. A sight tube 11 is mounted upon the boiler 60 near the top of the same so that the level of the water therein may be known at all times and a safety valve 12 is also provided at the top of the heater so that if the temperature of the water should rise to a danger point 65 the excess steam thereby generated may escape. In the lower end of the cylinder, at any convenient point thereof, I provide a drain cock 13 through which the water may be drawn off when it is desired to clean the 70 device or through which a quantity of hot water may be drawn for various domestic purposes. This drain cock may, of course, be caused to discharge into and through a hose or other connection so that the water 75 so drawn off may be carried to any desired point of use.

I have also shown in Fig. 1 upper and lower pipes 14 and 15, respectively, which communicate with the annular chamber or 80 compartment 2 and are provided with cut-off valves 16 so that the circulation therethrough may be controlled. These pipes 14 and 15 are connected by couplings 17 with pipes 18 connected to and communicating with the interior of a boiler 19 which may rest upon an ordinary kitchen range, indicated at 20. This boiler 19 may be of any desired detailed construction and will be provided with a removable cover so that water may be poured 90 into the boiler through the top thereof when it is to be used. A pipe 21 may lead from this boiler to a bath room and a draw off pipe 22 may also lead from the boiler to permit hot water to be drawn for any domestic 95 purpose.

The interior of the cylinder 1 is divided into a plurality of compartments by horizontal partitions which are preferably removable and are supported upon lugs, ribs 100 or flanges 23 formed on the inner wall of the cylinder. Communicating with each of the spaces defined by these partitions is a door 24 which is preferably hollow, as shown in Figs. 2 and 3, and filled with some heat-resistant packing, indicated at 25. Each door is provided with a damper 26 so that when desired the heat of the respective compartment may be reduced and each door is also provided with a latch 27 of any preferred 110 form so that it will be held against accidental opening. The partitions preferably con-

sist of semi-circular metal plates 28 and a layer 29 of asbestos or other heat-resisting material disposed upon the metal members. The asbestos layers are also semi-circular in form, this shape permitting the several members to be easily inserted through the doorway and placed upon the supporting lugs or ribs with their straight edges abutting so as to separate and define the several compartments and, by reference to the full and dotted lines in Fig. 2, it will be noted that the asbestos layers are disposed at right angles to the metal sheets so that the seam or joint between the metal members will be bridged by the heat-resisting covering.

As indicated in Fig. 3, food to be cooked is placed in convenient cooking vessels and the vessels containing the food then supported upon the partitions and the bottom 20 of the boiler or heater, after which the doors 24 are tightly closed. If the furnace is in use, the hot water will circulate through the pipes 8 and 9 and the water within the compartment or annular chamber 2 will be normally at a high temperature so that no further attention will be needed to accomplish the desired cooking. If, however, the furnace is not in use and it is not desired to heat water in the boiler 19, the burner 7 is 25 brought into use and the water in the cylinder or boiler 1 is thereby raised in temperature so that the inner wall of the cylinder will be heated and will throw off heat into the several compartments of the boiler and thereby accomplish the desired cooking. After the water in the annular chamber has 30 been brought to the boiling point or to an otherwise sufficiently high temperature, the flame at the burner 7 may be extinguished and the heat contained in the water will then 35 finish the cooking. If the kitchen range 20 is in use or it is desired to boil water in the vessel 19 for domestic use, it will not be necessary to utilize the burner 7 as by opening 40 the cut-off valves 16 a circulation of water through the pipes 14, 15 and 18 will be set up and the water in the cylinder 1 will be thereby brought to the desired temperature. When the furnace is in use, the valves 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810

needed, the water in the cooker may be raised to a cooking temperature very readily by the use of the burner 7 and, consequently, there is no wasting of fuel and heat is applied only where and as it is needed and a kitchen may be kept cool and comfortable. The apparatus is free of complicated constructions or arrangements and may be produced and installed at a low cost. It will be noted that each partition or shelf presents a metal surface on its under side and a heat-resisting layer on its upper side. The steam generated in the space below the partition will be permitted to play directly upon the metal partition members and will heat the same but the heat will not be permitted to escape from the upper side of the metal members, owing to the presence of the heat-resisting layer thereon. All the heat within any one compartment will, consequently, be held therein to perform its office of cooking and the door to any one compartment may be opened and the cooking in that compartment inspected without causing any chilling of any other compartment.

Having thus described the invention, what is claimed as new is:

1. In an apparatus for the purpose set forth, a double walled cylinder, spaced annular ledges around the inner wall of said cylinder, removable partitions consisting of a plurality of mating sheet metal members for each of said ledges and adapted to rest thereupon and dividing the interior of the cylinder into a plurality of compartments, heat resisting members having the same size and shape as said sheet metal members and adapted to rest thereupon, encased entrance openings being provided in the inner and outer walls of said cylinder, doors for said openings, said doors having recesses filled with heat resisting material, and a damper on each of said doors, said sheet metal members and said heat resisting members being of a size to pass through said entrance openings.

2. In an apparatus for the purpose set forth, a hollow cylinder with closed ends, a similar cylinder forming a casing around the first cylinder with a space for heating fluid between them, annular ledges within said first cylinder, partitions made in sections adapted to rest upon said ledges and dividing the interior of said first cylinder into a plurality of closed compartments, opposing openings in both cylinders for each compartment, connecting walls between the cylinders forming tight joints around said openings, and doors for closing said openings and provided with recesses filled with heat resisting material.

In testimony whereof I affix my signature.

WILLIAM A. PENROD, [L.S.]
